Primary Examiner — John Windmuller*Assistant Examiner* — John R Yeh(74) *Attorney, Agent, or Firm* — Duane Morris LLP; J. Rodman Steele, Jr.; Gregory M. Lefkowitz(57) **CLAIM**

The ornamental design for a clip, as shown and described.

DESCRIPTION

FIG. 1 is a right perspective view in accordance with a new clip design;

FIG. 2 is a front view of the design of FIG. 1;

FIG. 3 is a back view of the design of FIG. 1;

FIG. 4 is a right side view of the design of FIG. 1;

FIG. 5 is a left side view of the design of FIG. 1;

FIG. 6 is a top view of the design of FIG. 1;

FIG. 7 is a bottom view of the design of FIG. 1;

FIG. 8 is a front view showing the clip portion rotated 90 degrees clockwise; and,

FIG. 9 is a front view showing the clip portion rotated 90 degrees counter-clockwise.

The broken lines in the figures depict environment and portions of the clip that form no part of the claimed design.
